Inventor,
Lawson B. Shelton

UNITED STATES PATENT OFFICE.

LAWSON B. SHELTON, OF LOS ANGELES, CALIFORNIA.

HINGE.

1,334,563.

Specification of Letters Patent. Patented Mar. 23, 1920.

Application filed April 26, 1919. Serial No. 293,012.

To all whom it may concern:

Be it known that I, LAWSON B. SHELTON, a citizen of the United States, residing at Los Angeles, in the county of Los Angeles 5 and State of California, have invented a new and useful Improvement in Hinges, of which the following is a specification.

The object of my invention is to make a hinge, which when used to mount casement 10 windows to their frames, will permit the sash thereof, to be pressed down in front of the stool after closing the window, and my invention consists of the novel features herein shown, described and claimed.

15 The accompanying drawings illustrate my invention, in which,

Figure 1 shows a hinge embodying the principles of my invention.

Fig. 2 shows a surface appearance of the 20 hinge when complete.

Fig. 3 shows the pivot pin with spiral spring attached.

Referring to the drawings in detail, to describe my invention:—

25 Leaf 1, has the lower portion of its knuckle —2— raised away from the pivot pin —3— sufficiently to make room for a spiral spring —4—, to be mounted thereon, and said raised portion of the knuckle —2—, 30 has the end —5—, cut away to allow it to pass down over leaf —6—, at this point. The object of the spiral spring —4—, is to raise the leaf —1—, together with the window sash, when so attached, its upper end so

35 arranged to form a seat for the knuckle of leaf —1—. The pivot pin —3—, is fastened or rigidly placed in the upper knuckle —7— of leaf —6—, and may be slotted or grooved a part of its length to admit the upper end 40 of the spiral spring —4—, and allow it to travel freely therein. The lower end of the

spiral spring —4—, is fastened to a ring —8—, which encircles the pivot pin —3—, at its bottom, and is adapted to engage with the adjacent knuckle end —9—, of leaf —6—, at this point, and the meeting edges 45 may be serrated, so that the spring —4—, can be strengthened by winding. The remaining portion of the knuckle, shown at —5—, will rest on the part immediately below, when the window is open or ajar, and thus relieve the spiral spring —4—.

When the hinges are fastened in the usual way to an inner mounted casement window sash and frame, which has the usual inside 55 stool, the sash may be pressed down in front of the stool after closing, when a water tight joint is desired, and fastened.

Having thus described my invention, what I claim and desire to secure by Letters Patent of the United States, is,

1. In a hinge having the usual alining knuckles, held together by a pivot pin, of one of the knuckles arranged to slide on the pivot pin, at one point of its axis and be returned by means of a spiral spring encircling a portion of the pivot pin between the knuckle ends of the matched members, the said spiral spring so arranged, that it can be tightened to sustain more weight. 70

2. A hinge, one member of which, will slide down on the pivot pin, and thus permit the closure to be pressed down, and having adjustable means to counter-balance the weight of closure and having means to relieve the counter-balance when the closure is 75 open or ajar.

LAWSON B. SHELTON.
